UNITED STATES PATENT OFFICE.

ADOLPH OTTO URBAN, OF POINT ARENA, CALIFORNIA.

STARTING DEVICE FOR HYDRAULIC PUMPS.

1,403,138.

Specification of Letters Patent. Patented Jan. 10, 1922.

Application filed July 10, 1920. Serial No. 395,195.

To all whom it may concern:

Be it known that I, ADOLPH O. URBAN, a subject of the Republic of Austria, residing at Point Arena, in the county of Mendocino 5 and State of California, have invented new and useful Improvements in Starting Devices for Hydraulic Pumps, of which the following is a specification.

This invention relates to a new and useful 10 improvement in starting devices for hydraulic pumps and relates in particular to a device for starting a hydraulic ram.

The principal object of this invention is to produce a device of this character which 15 will operate upon a ram in such a manner as to start the same operating when, through lack of water, the ram has ceased to operate.

A further object of this invention is to provide a starting device for pumps which is 20 operated by the overflow from the source of supply and to provide an attachment which will not interfere with the delicate recoil of the pump.

A still further object is to produce a device 25 which is simple in construction, automatic in operation and one which may be attached to rams now in general use.

I propose to accomplish the above results by providing a simple means of automatically 30 opening the interrupter valve of the ram, thereby again starting the ram.

Other objects and advantages of the invention will be apparent during the course 35 of the following description:

In the accompanying drawings forming a part of this specification and in which like numerals are employed to designate like parts throughout the same,

Figure 1 is a diagrammatic view of a ram 40 having my starting device attached thereto,

Figure 2 is a side elevation of a portion of my starting device, and

Figure 3 is a cross-sectional fragmentary detail view of a bucket.

The operation of a ram is well known, and 45 is a device which is placed in a running stream, which device serves to lift a portion of the water passing there-through and deliver the same at some elevation above the ram. The lift is secured through the fact that the water flowing there-through is interrupted at intervals, which causes the inertia of the water trapped to be delivered at a distant point.

It is to the interrupter valve that my invention 50 will be attached,

In the drawings wherein for the purpose of illustration is shown a preferred embodiment of my invention, the numeral 5 designates a ram as a whole, and the numeral 6 60 the interrupter valve as a whole.

The pipe 7 is adapted to receive water from a source of supply here shown as a tank 8. This tank receives its supply through a pipe 9, the pipe 9 representing a 65 brook or any other source of supply.

The numerals 11 and 12 refer to standards positioned adjacent to the ram 5 and serving to support a bucket 13. This bucket is provided with ears 14 and 16 which serve 70 to guide the same upon the standards 11 and 12.

At 17 I provide a brace which forms a stop to limit the downward movement of the 75 bucket 13. This brace also serves to support a valve adjustment screw 18, which screw is adapted to be adjusted so as to contact with a valve 19 formed in a spigot 21 carried upon the bucket 13.

This bucket 13 is provided across its top 80 with a brace 22 to which is attached a screw eye 23 through the medium of a bolt 24. To this screw eye is attached a link 26, which in turn is attached to the end of a lever 27, which lever is fulcrumed at 28 in the top of 85 the standard 11 and is provided with a long arm 29 having a weight 31 movable thereon.

At 32 I have shown a lever adapted to contact with the arm 29 and attached at its lower end to the standard 11, through the 90 medium of a pin 33. This lever 32 may be lowered by moving the pin 33 to any one of the holes 34.

The numeral 36 designates an overflow pipe extending from a point near the top of 95 the receptacle 8 to a point within the top of the bucket 13.

At 37 I have shown an arm pivoted at 38 to a bracket 39 attached to the ram 5. This arm 37 is normally adapted to rest above the stem 41 of the interrupter valve 6 and is adapted to have its free end engaged by a pin 42 passing there-through and secured to the bucket 13. Between the arm 37 and the stem 41 there is a space provided when 100 the arm is in its normal position. The position of the arm 37, as shown in Figure 2, sets forth the position of the bucket when it is down causing the stem of the valve to be depressed. The arm 37, it will be observed, 105 will move upwardly and downwardly with the bucket and will cause an adjustable 110

screw 43 mounted thereon to contact with the valve stem 41 only after the bucket has in its downward movement acquired a sufficient momentum to overcome the counter-weight and the pressure under the valve. The above mentioned screw 43 on which are mounted nuts 44, is provided to allow different adjustments of arm 37 in order to have it disposed on a level from the pivot point 38 to the pin 42 no matter what the height of the valve stem 41 may be.

In operation water flows from the source of supply to the tank 8 through the pipe 7 through the ram 5 and causes the same to operate, it being assumed that the operation has been started.

Now, assuming that the water supply lowers to a point where it is not sufficient to work the ram, the interrupter valve 6 will close, thereby causing the water to accumulate in the tank 8, due to the fact that it can not pass through the ram 5.

This accumulation will result in the water overflowing through the pipe 36 and discharging into the bucket 13, and as the bucket is empty, it will be in its dotted position as shown in Figure 1. As soon as the same is sufficiently filled to overcome the weight 31, the bucket will move downwardly. This will cause the interrupter valve stem 41 to be depressed and at the same time the valve 19 will have been lifted through the action of the valve adjustment screw 18, which will allow the water within the bucket 13 to escape, and will again allow the bucket to return to its normal posi-

tion, which action carries the arm from its contacting position to its normal position. This depression of the valve stem 41 will have started the ram to operate, which operation will continue until the supply in the tank 8 has become exhausted after which the operation just described will be repeated.

It will thus be seen that I have created a device for automatically starting a ram, which will need practically no attention.

It is to be understood that the form of my invention herewith shown and described, is to be taken as a preferred example of the same, and that various changes in the shape, size and arrangement of parts may be resorted to without departing from the spirit of the invention or the scope of the subjoined claim.

Having thus described my invention, I claim:—

In an automatic starting device for hydraulic rams, the combination of an interrupter valve, a lever adapted to contact and depress said valve, a bucket adapted to actuate said lever, a reservoir, overflow means for conducting fluid from said reservoir to said bucket, an adjustable element for controlling the downward movement of said bucket when full of fluid and to raise said bucket when empty, and adjustable means for emptying said bucket when said bucket has reached the limit of its downward movement.

In testimony whereof I affix my signature.

ADOLPH OTTO URBAN.
